ADJUSTABLE SCAFFOLD HOIST

Laverne V. Phillips, Mitchell, S. Dak.

Application October 19, 1951, Serial No. 252,123

1. Claim. (Cl. 304—29)

1

The present invention relates to an adjustable scaffold hoist and it consists in the combinations, constructions and arrangements of parts herein described and claimed.

Generally there is provided a plurality of substantially rectangular units each having a vertically extending leg member at each corner thereof and the legs of each of the succeeding units being telescoped within the corresponding legs of the unit therebelow. Each unit is provided at each of its narrower ends with a V-shaped bracket which normally extends below an upper cross arm of the unit therebelow and is connected therewith by falls which are, in turn, connected with a centrally disposed winch carried by the lowermost unit. A motor is likewise carried by the lowermost unit and may be controlled from the uppermost unit, if desired, or from any other convenient position. One of the principal features of the invention is that the various cables emanating from the falls constitute in themselves a safety factor since the accidental breaking one of such cables will still leave the remaining cables in a position to maintain the device in whatever position in which it then may be.

It is accordingly an object of the invention to provide an apparatus of the character set forth which is exceedingly simple in construction, inexpensive to manufacture, easy to repair by those of normal skill and yet effective and efficient in use.

Another object of the invention is the provision of an apparatus of the character set forth having novel means for raising and lowering the same.

A further object of the invention is the provision, in an apparatus of the character set forth, of a novel extensible ladder forming a part of the invention.

Other and further objects of the invention will become apparent from a reading of the following specification taken in conjunction with the drawings, in which:

Figure 1 is a side elevational view of an embodiment of the invention;

Figure 2 is a top plan view thereof;

Figure 3 is a sectional view taken along line 3—3 of Figure 1;

Figure 4 is a sectional view taken along line 4—4 of Figure 2;

Figure 5 is an end elevational view of the apparatus showing the same in partially collapsed condition;

Figure 6 is a sectional view taken along line 6—6 of Figure 5;

Figure 7 is a view similar to Figure 5 but showing the apparatus in extended position,

2

Figure 8 is a sectional view taken along line 8—8 of Figure 7.

Figure 9 is a fragmentary perspective view illustrating certain details of construction,

5 Figure 10 is an enlarged fragmentary sectional view taken substantially along line 10—10 of Figure 2.

Figure 11 is an enlarged fragmentary sectional view taken substantially along line 11—11 of Figure 2.

10 Figure 12 is an enlarged fragmentary side elevational view illustrating in details features of construction, and

Figure 13 is a fragmentary side elevational view illustrating a winch and motor forming a part of the invention.

Referring more particularly to the drawings, there is shown therein an embodiment of the invention in which there is provided three units, 20 namely a bottom unit generally indicated at 10, an intermediate unit generally indicated at 11 and a top unit generally indicated at 12. Each of the units is generally rectangular in shape when viewed from above or below.

25 The bottom or base unit 10 is provided at each corner with a vertically extending hollow cylindrical leg 13, the end legs in each case being interconnected at their upper ends by an upper cross bar 14 and at their lower ends by a lower cross bar 15. The legs 13 at either side of the unit 10 are interconnected by side bars 16 which extend inwardly therefrom and which are connected to side plates 17 in an adjustable manner, as indicated at 18. The side plates 17 are

30 interconnected by a pair of spaced parallel supporting bars 19 from which a platform 20 is independently supported by legs 21. Adjustable truss members 22 interconnect the plates 17 and the lower portions of each of the legs 13 and bracket

35 members 23 interconnect the inner portions of each of the members 16 with the upper portion of the adjacent legs 13 to provide additional rigidity to the members 16.

40 Each of the cross bars 14 has affixed thereto an inwardly extended U-shaped bracket 24 in which is revolubly mounted a pulley 25. In the lower end of each of the legs 13 there is mounted in the present form of the invention a caster 26 for supporting the entire apparatus. However, it will be apparent that the base unit 10 may be mounted upon a truck or other vehicle or may be provided with means of locomotion in itself.

45 The intermediate unit 11 is likewise provided with a vertically extending hollow cylindrical leg 27 at each of its corners which legs are telescopically mounted in each of the legs 13 respectively and the legs 27 at each end of the unit 11 are

interconnected by a cross bar 28 adjacent the upper end thereof and each is provided with an inwardly extending horizontal side bar 29 whose inner ends are receivable telescopically within a cylindrical member 30.

Vertically dependent from each of the bars 28 is a V-shaped bracket 31 in the lower or apex portion of which is mounted a pulley 32.

Referring now to the top unit 12 there is likewise provided at each corner thereof a hollow cylindrical leg 33 which extends vertically and telescopically into the leg 27 and the legs 33 at each of the shorter sides of the unit 12 are interconnected adjacent their upper ends by a cross bar 34 and each of the legs 33 is provided with a horizontally and inwardly extending bar 35 which is telescopically receivable at its inner end in a hollow cylindrical member 36. To the outer side of each of the cross bars 34 there is dependently and vertically mounted a V-shaped bracket 37 in the lower or apex portion of which there is mounted a pulley 38.

Each of the cross bars 28 has affixed to the outer side thereof a U-shaped bracket 39 in which is revolutely mounted a pulley 40. Upon the platform 20 there is mounted an electric motor 41 which is connected by means of a belt 42 with a pulley 43 affixed to one side of a drum 44. The drum 44 has affixed thereto a ratchet wheel 45 with which a pawl 46 is engaged. The pawl 46 is revolutely mounted upon an ear 47 carried by one of the legs 21 and a compression spring 48 is interposed between the pawl 46 and the leg 21 with which it is associated.

A cable is affixed, as indicated at 49, to the outer end of each of the brackets 24 and extends downwardly, as indicated at 50, whence it is entrained over the pulley 32 and thence extends upwardly over the pulley 25 and thence to the drum or winch 44. Likewise to each of the brackets 39 there is affixed a cable 51 which extends downwardly and is entrained over its associated pulley 38 and thence extends upwardly over the pulley 40 and thence to the winch 44.

In the upper ends of each of the pairs of end legs 33 there is telescopically mounted the legs 52 of a U-shaped fence member 53. At various points about the apparatus the corner portions may be interconnected by plates 54 or the like to provide additional rigidity to the apparatus.

In operation, it will be apparent that the device may be normally in a collapsed condition as shown, for example, in Figure 5 and that when it is desired to raise the same to be used as a scaffold, it is only necessary to operate the motor 41 which operation may take place from the uppermost or top unit 12 by remote control and that when such action occurs the winch 44 will act to wind thereon the cables 50 and 51 to thus raise the V-shaped brackets 31 and 37 and by the same token move the legs 27 out of the legs 13 and at the same time the legs 33 out of the legs 21. As this action occurs, the pawl 46 will allow the teeth of the ratchet wheel 43 to pass thereby and thus it will be seen that as the top unit 12 is raised to desired position, that the same will automatically be locked in such position until it is desired to lower the apparatus which may be done in any suitable manner preferably by utilizing a brake in connection with the winch 44 in conventional manner at which time, of course, the pawl 46 will be disengaged from the ratchet wheel 43.

At one end of the apparatus there is provided a vertically dependent ladder which is affixed

to the cross bar 34 and which ladder is indicated at 54a. A like ladder 55 is vertically dependent from the cross bar 28 and underlies the ladder 54a. A ladder 56 is formed as a part of the lower or base unit 10 and consists of one of the legs 13 together with a parallel interconnecting leg 57 and a plurality of rungs 58 which interconnect the leg 57 with the adjacent leg 13. It will be seen that the ladder 54a extends slightly outwardly of the plane of the leg 33 while the ladder 55 extends slightly inwardly of the leg 27 to thus afford clearance of such ladders when the apparatus is collapsed. Likewise the ladder 56 is in the same plane as the legs 13 to further avoid any interference with the ladders 54a and 55 when the apparatus is in collapsed condition.

While but one form of the invention has been shown and described herein, it will be readily apparent to those skilled in the art that many minor modifications may be made without departing from the spirit of the invention or the scope of the appended claim.

What is claimed is:

An apparatus of the character described comprising a base unit, an intermediate unit, and a top unit, each of said units being generally rectangular in plan view, and each being telescopically mounted in the unit next therebelow, means for simultaneously extending the intermediate and top units upwardly with respect to the base unit, said base unit having a hollow cylindrical vertically extending leg in each corner thereof, said intermediate members having a hollow cylindrical vertically extending leg in each corner thereof and each vertically slidable in a leg of the base unit, and said top unit having a vertically extending leg in each corner thereof, each vertically slidable in one of the legs of the intermediate unit, a cross bar interconnecting the upper end portions of each pair of legs at each end of each unit, a dependent V-shaped bracket affixed to the outer side of each cross bar of the top unit, a dependent V-shaped bracket affixed to the inner side of each of the cross bars of the intermediate unit, a pulley centrally mounted on the outer side of each cross bar of the intermediate unit, a pulley centrally mounted on the inner side of each cross bar of the base unit, a pulley mounted at the lower end of each V-shaped bracket, a winch mounted on the base unit, cables each affixed at one end to each cross bar of the base unit and of the intermediate unit and each extending downwardly and entrained under the pulley on the bracket of the next uppermost unit and thence upwardly and over the adjacent pulley carried by the cross bar of its associated unit and thence extending to and connected with said winch.
